UNITED STATES PATENT OFFICE.

TIMOTHY DOLAND, OF WELLINGTON, OHIO.

ROAD-CART.

SPECIFICATION forming part of Letters Patent No. 392,414, dated November 6, 1888.

Application filed July 23, 1888. Serial No. 280,781. (No model.)

To all whom it may concern:

Be it known that I, TIMOTHY DOLAND, a citizen of the United States, residing at Wellington, Lorain county, and State of Ohio, have 5 invented certain new and useful Improvements in Road-Carts; and I do hereby declare the following to be a full, clear, and true description thereof.

The nature of my invention relates to certain constructions and adjustments of the seat and foot-rest of a road-cart to render it easy and convenient for getting in and out thereof and to adjust the seat to various loaded conditions under which it is to be used.

15 That the improvements may be fully seen and understood, reference will be had to the following specification and the annexed drawings, making part thereof.

Figure 1 is a side view of a road-cart having one of the wheels removed. Fig. 2 is a cross-section of the same on line $x x$, as seen from the rear side of the cart.

Like letters of reference denote like parts in the drawings and specification.

25 The cart, as illustrated in Fig. 1, has one of its wheels removed to permit of a full view of the several parts forming the essential features of this invention.

A indicates the axle, and B one of the 30 wheels. To the axle are secured the shafts C C by means of the clamps D and the braces E, Fig. 1. The cross-bar F braces the shafts laterally and serves as a support for the spring G, as seen in Fig. 2, which spring is 35 for the purpose of cushioning the seat-bars H H and seat mounted upon the bars to which the seat is fastened. The opposite ends of these bars are attached to the shafts C C by a hinged connection, J, which admits of 40 an easy movement of the seat in its relation with the spring G. In both ends of this spring is an eyebolt, K, as seen in the drawings. One end of the loop L is attached to said eyebolt. This arrangement of the loop, eyebolt, and connection with the spring G is the 45 same on both sides of the cart. The loops L L embrace both of the seat-bars H H, to which the notched plates M M are fastened on the under side, as shown in the drawings. By 50 means of the said plates the loops L L are retained in the notches thereof at various distances from the hinged connections J J of the seat-bars with the shafts.

The dotted lines $a a'$ indicate the different

positions in which the loops may be set. For 55 light use the loops will be set in the plate-notch indicated by the lines a , and for heavy use or load into the plate-notch corresponding with the line a' . Thus the strain or weight on the spring G is regulated in so far as a light 60 person or load is concerned. In such instance more leverage on the spring may be had than a heavy person or load. This change of leverage on the spring is attained by adjusting the loops L L to the proper plate-notch, as before 65 indicated by the lines $a a'$, Fig. 1.

The foot-rest consists of the hangers N N and the cross-bars O, the hangers being attached to the under side of the seat-bars H H at one end, while the other ends are connected by a 70 jointed attachment to the bolt K. By this means the foot-rest movements conform with that of the seat when used and render riding easy and comfortable. The seat is readily adjusted in the required position by lifting it at 75 the rear end, by which the loops may be swung or adjusted into notches of the plate M, according to the load of the cart. As the seat-bars extend under the cross-bar F, (shown in the drawings,) this arrangement facilitates 80 getting in and out of the cart.

What I claim, and desire to secure by Letters Patent, is—

1. In combination with a road-cart, the seat-bars H H, having jointed connections J J with 85 the shafts, loops L L, engaging the notched plates attached to the seat-bars, and a jointed connection with the spring G, attached to the cross-bar F of the foot-rest, supported by its hangers N N, being fastened to the seat-bars 90 and a jointed attachment to the spring G, respectively arranged as and for the purpose substantially as set forth.

2. In combination with a road cart, the foot-rest hangers N N, attached at one end to the 95 seat-bars H H and the opposite ends thereof jointedly connected to the seat-bar spring G, arranged to co-operate conjointly with the seat and seat-bars, having a hinged connection with the shafts, substantially as and for the 100 purpose set forth.

In testimony whereof I affix my signature in presence of two witnesses.

TIMOTHY DOLAND.
